Primary Examiner — John Windmuller(74) *Attorney, Agent, or Firm* — Wolf, Greenfield & Sacks, P.C.**CLAIM**

The ornamental design for a mated fluidic connector, as shown and described.

DESCRIPTION

FIG. 1 is a top, front, right side perspective view of the mated fluidic connector;

FIG. 2 is a front elevational view of the mated fluidic connector;

FIG. 3 is a rear elevational view of the mated fluidic connector;

FIG. 4 is a left side elevational view, the right side being a mirror image thereof, of the mated fluidic connector;

FIG. 5 is a top plan view of the mated fluidic connector; and, FIG. 6 is a bottom plan view of the mated fluidic connector. Only the portion of the mated fluidic connector in solid lines is claimed. The portion of the figures shown in dashed lines forms no part of the claimed invention.

1 Claim, 5 Drawing Sheets(56)
